UNITED STATES PATENT OFFICE.

JULIAN L. PERKINS, OF WEST SPRINGFIELD, AND HIRAM D. CROFT, OF SPRINGFIELD, MASSACHUSETTS, ASSIGNEES TO PERKINS MACHINE AND GEAR COMPANY, OF SPRINGFIELD, MASSACHUSETTS, A CORPORATION OF MASSACHUSETTS.

BROACH MECHANISM.

Application filed April 7, 1927. Serial No. 181,842.

Our invention relates to improvements in mechanisms for carrying and holding broaches and moving them into and out of cutting position, and resides in a carrier 5 adapted to be attached to the reciprocating element of a broaching machine, a holder for a line or lines of broaches, links pivotally connected with said holder and pivotally mounted on eccentric members with which 10 said carrier is provided, means to adjust said eccentric members, on their axes, an abutment or abutments for said holder, actuating means for said holder, and means to secure the broaches to the holder, together 15 with such other parts and members as may be necessary or desirable in order to render the mechanism complete and serviceable in every respect, all as hereinafter set forth.

The primary object of our invention is to 20 provide comparatively simple, yet highly efficient, means for holding and presenting a broach or broaches for action on the work, and for giving to said broach or broaches, when desired, a lead or leads that can be 25 varied at will and with great minuteness, whereby it is possible to obtain the utmost accuracy and the greatest efficiency with the broach or broaches with which this mechanism is equipped.

Another object is to provide simple and 30 entirely practical means for moving the broach or broaches into the cutting field and removing them therefrom, such means being operated to move the broaches into the cutting field before they arrive at the work, and 35 to remove them from said field after they have passed completely through the work.

A further object is to supply mechanism 40 of this character with strong and entirely adequate means for securing the broaches or broach sections so firmly and rigidly to the holder that any displacement of the same, except when released for removal is prevented.

Other objects and advantages will appear 45 in the course of the following description.

We attain the objects and secure the advantages of our invention by the mechanism illustrated in the accompanying drawings, in 50 which—

Figure 1 is a side elevation and partial section of a broach mechanism which embodies a practical form of our invention; Fig. 2, a front elevation of an intermediate portion

of said mechanism, which includes the actuating means for the broach holder, parts being broken away and a portion of the operating lever being broken out; Fig. 3, an enlarged, fragmentary portion in section of the carrier, showing one of the eccentric members mounted therein; Fig. 4, an enlarged, top plan of the holder, one of the broach sections, and the clamping means therefor, and, Fig. 5, a side elevation of parts corresponding with those shown in the preceding view.

Similar reference characters designate similar parts throughout the several views.

We have illustrated in connection herewith, and will describe, broach mechanism 70 which is designed to be equipped with both roughing and finishing broaches, but it is to be understood that the number of broaches or lines of broaches is not material, so far as the present invention is concerned; inasmuch as there may be only one broach or one line of broaches, or more than two broaches or two lines of broaches.

Our mechanism includes a channeled carrier 1 opening through one longitudinal 80 edge to receive a holder, which holder constitutes an element of said mechanism presently to be described. Mounted for rotary adjustment in the carrier 1, behind the channel therein, are four spindles 2, each having an intermediate, cylindrical portion which forms an eccentric 3. Each spindle 2 has at one end a protruding angular projection 4 to receive thereon a sector 5 in which is a segmental slot 6. Each sector 5 extends forwardly from the projection 4 on which it is mounted, alongside of the flange of the carrier 1 which is on the same side with said sector, and a bolt 7 is passed through said flange from the inside and through the slot 6 in the sector to receive on its outer terminal a nut 8. Although but one of these sectors, with its bolt and nut, is shown in the drawings, it is to be understood that each spindle 2 is provided with similar adjusting 95 and clamping means therefor.

Upon loosening the nut 8 in any case, the associated sector and the spindle 2 on which said sector is mounted can be rotated in either direction to change the position of the eccentric 3 on said spindle, and locate the axis of said eccentric either forwardly or rearwardly as desired and to whatever ex-

tent required. After adjustment the nut 8 is retightened.

In the present example, there is a line of roughing cutters or broaches 9, and also a line of finishing cutters or broaches 10, the teeth of these broaches being arranged and constructed to cut on the down stroke, and the finishing broaches being above the roughing broaches. For these lines or sets of cutters 9 and 10 we provide a holder comprising a long section 11 for the roughing cutters, a short section 12 for the finishing cutters, and a connecting bar 13 between said sections, the opposite end portions of said bar being attached to adjacent ends of said sections by pins 14—14. The end portions of the bar 13 are let into recesses in the adjacent end portions of the sections 11 and 12, with the back or inner side of said bar flush with the corresponding sides of said sections. The aforesaid recesses produce lugs 15 and 15', respectively, at adjacent ends of the holder sections 11 and 12. The lugs 15 and 15' extend onto the front side of the bar 13, and it is through said lugs that the pins 14 extend.

A link 16 is mounted at the rear end on each of the eccentrics 3, and is pivotally connected at the opposite end with either 30 the holder section 11 or the holder section 12, as represented at 17, the carrier 1 and both holder sections being recessed at 18 and 19, respectively, to accommodate said link and afford ample spaces for whatever movement on the part of the link is required.

An abutment block 20 is secured by bolts or other means in the top of the channel in the carrier 1, above the holder section 12, and an abutment block 21 is similarly secured in said channel, in front of the bar 13 and above the holder section 11. The blocks or abutments 20 and 21 are arranged to limit the upward movement of the holder sections, and receive the thrust imparted to said sections by the cutters when making their active stroke.

The holder section 12 is formed with an inset 22 to receive the finishing cutters 10 and position them approximately in the longitudinal center, laterally, of said section, with their teeth projecting beyond the front edge of the section, and each of said cutters is secured to the section by means of a clamp 23 and a bolt 24. The inner and outer major planes of the clamp 23 are in angular relationship to each other, and the bolt 24 passes through an opening in said clamp which is at right-angles to the outer face thereof, and is tapped into an opening in the holder section 12 at an angle which corresponds with the angle of said opening in said clamp for the passage of said bolt. There must also be an oblique opening in each cutter 10 to receive the bolt after it passes through the clamp 23 and before entering the holder

section. When the bolt 24, after being passed through the clamp 23 and cutter 10 into the holder section 12, is tightened, it not only forces said clamp hard against said cutter, so that the latter is tightly grasped between the contiguous surface of the inset 22 and that of said clamp, but also tends to force said cutter rearwardly or inwardly against the back end of said inset, and thus to retain the cutter securely in place with its rear edge against said back end.

The individual roughing cutters 9 are longer than the individual finishing cutters 10, and the former are secured to the holder section 11 by means of clamps 23 and bolts 24 in a similar manner as the latter are secured to the holder section 12, except that less clamps and bolts are needed for the longer individual cutters.

Journaled in a horizontal bearing 25, supported from a bracket 26 secured by bolts or other means to one side of the carrier 1, on the outside thereof, is a rock shaft 27. Mounted on and secured to the outer end of the rock shaft 27 is an operating arm 28, and mounted on and secured to the inner end of said shaft is an actuating arm 29. The arm 28 at its outer end is designed to be connected with mechanism (not shown) for intermittently rocking said arm and with it the shaft 27 and the arm 29, first in one and then in the other direction. The arm 29 extends through a slot 30, in the side of the channel in the carrier 1 to which the bracket 26 is fastened, into a recess 31 in the holder bar 13.

When the arm 28 is actuated in one direction, the arm 29 is actuated in the opposite direction and carries with it the bar 13 and the connected holder sections 11 and 12, and when said first-named arm is rocked in the other direction, said second-named arm is rocked in the opposite direction again and carries with it said bar and sections. The abutments 20 and 21 limit the movement imparted to the broach holder at the time the arm 28 is rocked downwardly. Means to limit the movement of the holder in the opposite direction is not needed, because the broaches or cutters are then out of operative position and no end support for the parts is required, as is the case when said cutters are in operative position and making their cut.

In practice, the holder sections 11 and 12 are adjusted to cause the cutters 9 and 10, when in the cutting field to be projected a proper distance therein, and either or both cutters to be provided with a lead or leads if and as necessary, by loosening the locking means for the spindles 2, partially rotating said spindles to the extent required to advance or retract, by means of the eccentrics 3, and through the mediums of the links 16, the sections 11 and 12, and then relocking said spindles against further rotation. By this means and in this manner the holder

section 12 can be set so that the broaches 10 have a lead over the broaches 9; or both sets of broaches can be set so that the upper end has a lead over the lower end of each; and, 5 in any event, the sections 11 and 12 are set to enable the broach teeth to be located exactly in the cutting plane, when the cutters are in advanced and broaching position.

The cutters 9 and 10, as disposed in the 10 first view, are in an intermediate or neutral position, from which position they are moved into active position when the arm 28 is rocked downwardly, and into normal inactive position when said arm is rocked upwardly. The arm 28 is rocked downwardly to locate the holder sections 11 and 12 against the abutments 21 and 20, respectively, before the carrier 1 is caused to descend. During the descent of the carrier 1 the cutters 9 and 20 10 make their cut. As soon as the cutters 10 clear the work, the arm 28 is actuated to carry the holder with said cutters downwardly in the carrier 1. This downward movement on the part of the holder and cutters 25 is converted into a rearward movement through the medium of the links 16, and the cutters are thus retracted from the cutting field, and they are not again advanced into said field until the carrier 1 has ascended 30 and is about or commences to descend to make the next cut. Being retracted, at the time the carrier 1 ascends, the cutters 9 and 10 clear the work. The mechanism that controls the movement of the arm 28 necessarily 35 serves to control or limit the downward movement of the holder and its cutters.

The slot 30 in the carrier 1 is of sufficient length to enable the arm 28 to swing up and down therein to the extent needed for moving the bar 13 the required distance.

More or less change in the shape, size, construction, and arrangement of some or all of the parts of this broach mechanism may be made, without departing from the spirit 45 of our invention or exceeding the scope of what is claimed.

What we claim as our invention, and desire to secure by Letters Patent, is—

1. In mechanism of the class described, 50 members, one of which is adapted to hold broaches, in sliding relationship, adjustable pivotal means carried by one of said members, and connections mounted on said pivotal means and pivotally connected with the other of said members.

2. In mechanism of the class described, 55 members, one of which is adapted to hold broaches, in sliding relationship, adjustable pivotal means carried by one of said members, means to lock and release said pivotal means, and connections mounted on said pivotal means and pivotally connected with the other of said members.

3. The combination, in mechanism of the 60 class described, with a carrier, a broach

holder in sliding relationship to said carrier, and pivotal connecting means between said holder and carrier, of means to move said holder longitudinally on said pivotal means, the construction and arrangement of parts 70 being such that the longitudinal movement of said holder is converted into a movement in the direction of a transverse dimension of said holder.

4. The combination, in mechanism of the 75 class described, with a carrier, a broach holder in sliding relationship to said carrier, and pivotal connecting means between said holder and carrier, of means to move said holder longitudinally on said pivotal means, the construction and arrangement of parts 80 being such that the longitudinal movement of said holder is converted into an arcuate movement which positions the holder in different vertical planes.

5. The combination, in mechanism of the 85 class described, with a carrier provided with an abutment, a broach holder in sliding relationship to said carrier, said abutment being in the path of said holder, and pivotal connecting means between said holder and carrier, of means to move said holder longitudinally on said pivotal means, the construction and arrangement of parts 90 being such that the longitudinal movement of said holder is converted into a movement in the direction of a transverse dimension of 95 said holder.

6. In mechanism of the class described, a 100 carrier, spindles provided with eccentrics mounted in said carrier, a broach holder slidably arranged relative to said carrier, links mounted on said eccentrics and pivotally connected with said holder, and means to actuate said holder longitudinally.

7. In mechanism of the class described, 105 a carrier, spindles provided with eccentrics mounted in said carrier, means to lock said spindles against rotation and to release the same, a broach holder slidably arranged relative to said carrier, links mounted on said eccentrics and pivotally connected with said holder, and means to actuate said holder longitudinally.

8. The combination, in mechanism of the 110 class described, with a carrier, spindles provided with eccentrics mounted in said carrier, sectors secured to said spindles, means to hold said sectors against independent movement after the same with their spindles have been partially rotated for the proper adjustment of said eccentrics, a broach holder slidably arranged relative to said carrier, and links mounted on said eccentrics and pivotally connected with said 115 holder, of means to actuate said holder longitudinally.

9. The combination, in mechanism of the 120 class described, with a carrier, a broach holder slidably arranged relative to said 125

holder, of means to actuate said holder longitudinally.

carrier, and links pivotally connected with said carrier and with said holder, of a rock shaft mounted on said carrier, and provided with an arm in engagement with said holder, and with an operating arm.

10. The combination, in mechanism of the class described, with a carrier, a broach holder slidingly arranged relative to said carrier, said holder comprising upper and 10 under sections and a connecting bar, and links pivotally connected with said carrier and with said sections, of a bearing attached to said carrier, and a rock shaft journaled in said bearing, and having an operating 15 arm and an arm in engagement with said bar.

11. The combination, in mechanism of the class described, with a channeled and slotted

carrier provided with abutments, spindles provided with eccentrics and mounted in 20 said carrier, locking and releasing means for said spindles, a broach holder slidingly arranged in the channel in said carrier, said holder comprising sections each located below one of said abutments, and a connecting 25 bar, and links mounted on said eccentrics and pivotally connecting with said sections, of a bearing attached to said carrier, a rock shaft journaled in said bearing and having one terminal adjacent to the slot in 30 said carrier, an arm secured to said shaft and extending through said slot into engagement with said bar, and an operating arm also secured to said shaft.
